UNITED STATES PATENT OFFICE.

CHARLES F. LAWTON, OF ROCHESTER, NEW YORK, ASSIGNOR TO ROBERT H. SALMONS, OF SAME PLACE.

METHOD OF AND APPARATUS FOR THE MANUFACTURE OF BEER.

SPECIFICATION forming part of Letters Patent No. 468,809, dated February 16, 1892.

Application filed October 3, 1890. Serial No. 366,950. (No model.)

To all whom it may concern:

Be it known that I, CHARLES F. LAWTON, a citizen of the United States, residing at Rochester, in the county of Monroe and State of New York, have invented certain new and useful Improvements in the Method of and Apparatus for the Manufacture of Beer, of which the following is a specification.

My invention relates to an improved method of and apparatus for the manufacture of beer; and it consists in various features hereinafter set forth and claimed.

The object of the invention is the rapid fermentation of beer, ale, and wine under conditions that prevent the introduction and growth of deleterious ferments in the liquor while subject to the action of the proper yeast ferment.

I will now describe the preferred form of apparatus for carrying out my process, as represented in the annexed figure, which is an elevation of the apparatus mainly sectioned in a vertical plane.

A indicates an air-filter comprising a metallic vessel A', filled with clean cotton.

B indicates a pump communicating with the filter by a pipe a', having a valve a, and communicating also by means of a pipe a'' with the bottom of a strong metallic vessel C, which is filled with asbestos or sand, as at c'. A pipe c'', having a valve d, extends from the top of the vessel C to a vessel D, while from the vessel D extends a pipe d', having a valve e. The vessel C is surrounded by a jacket C', while the vessel D is surrounded by a similar jacket D', the spaces between the vessels and the jackets being filled with any suitable non-conductor of heat. The pipes a'' and c'' are likewise jacketed, so as to prevent the heated air or gas from being cooled. The pipe d', extending from the lower end of the compressed-air reservoir D, communicates with a coil or manifold E, upon which water from a pan or receptacle f is designed to fall to cool the gas or air under pressure.

This manifold or coil communicates with a pipe k, extending along beneath the tuns or vats G G, while branch pipes k', having valves l, extend from the pipe k up through the bottom of the tuns, where they are provided with finely-perforated arms g. The tuns are pro-

vided with covers W, having downwardly-turned edges to dip into a liquid in a trough W', secured to the tuns, as shown, the liquid being advisably combined with an antiseptic to prevent any foreign ferments passing into the interior of the tuns. Tuns G are further provided with funnels i, having valves u, by means of which the tuns may be filled; but instead of the funnels the vertical pipe h may be used for filling. Opening into the top of the tuns is a U-shaped pipe l', which communicates at its outer end with a pipe M, extending over all of the tuns. This pipe extends downward to the drip receiver or reservoir O and intersects the pipe a' and is provided on each side of the pipe a' with a valve R R'. When it is desired to compress and force into the wort a gas different from common air, the valves a and R will be closed and the valve R'' on the pipe N opened. This branch pipe N, whose whole length is not shown, communicates with the holder containing the gas that is to be pumped into the fermenting-wort.

The tuns G will each be provided with a thermometer j, by means of which the temperature of the wort may be readily determined.

Surrounding the air and gas pump B is a tank b, which may be partly filled with water when the pump is being rapidly worked at a high pressure. This water prevents the lower part of the barrel of the pump and the piston inside of it from heating to that degree as to cause cutting of the working parts. As the compressed air passes so quickly out of the pump, this cooling of the outside of the barrel of the pump will not materially lower the temperature of the compressed air that is driven into the second air-filter C and compressed-air receiver D.

Should it be desired to aerate new hot wort recently let into one or several of the fermenting-tuns, or should it be desired to aerate, cool, and purify fermenting wort that has become unclean or sickened, or shows signs of becoming so, then the valves R, R', and R'' are closed, the valve a opened, the valve e shut or but slightly opened, and the pump set in motion.

The accumulation of compressed air in the

filter C and receiver D rapidly heats it, together with the walls of the containing-vessels, surrounded, as they are, by non-conductors, to such a temperature as to destroy noxious ferment-germs. The first of the air that is run through the manifold E and pipe k from the compressed-air receiver D is allowed to escape without being run into the wort, as usual. This is to get rid of stagnant air that may have lain in the manifold E or pipe k.

The compressed-air filter C being packed with asbestos or fine sand, the heat evolved by the compression does not char or set fire to it, as it would if the filter C was packed with cotton like the filter A, which is not subjected to compressed air.

The valve e, (leading from the compressed-air receiver D to the manifold E,) having but a small opening when used with compressed air, prevents any back-circulation into receiver D of cooled compressed air in manifold E or pipe k. Without covering the compressed-air filter C and compressed-air reservoir D with a thick coat of non-heat-conducting material the compression of the air in these vessels would not heat it sufficiently to properly sterilize it.

When everything is ready for the use of the compressed and sterilized air, the valves l of one or more of the fermenting-tuns are very slightly opened, and the air escaping through this valve up into the wort expands and consequently absorbs heat while in the immediate presence of the beer or wort to be cooled and aerated. By this means the refrigerating effect of the compressed air is obtained with the greatest possible economy of power and plant, and aeration is obtained simultaneously with cooling, which is of considerable advantage, as cold air is more freely absorbed by watery liquids than is warm air. The previously-strained hot wort is run from the vessel, where it has been boiled down with the hops, by a flexible pipe or hose to the funnel i, through which it enters the tuns. As soon as the tun is filled to the proper height the stream of boiling wort is shut off and the valve u in the funnel closed. The hot wort is left in the tun until the heat it carries has killed such injurious ferments as might adhere to the inside of the tun and its cover and such germs as might be on or in the pipes g and h. This large body of heated wort will remain very hot for a long time; but after it has stood long enough to kill the germs of injurious ferments the strongly-compressed properly-cooled air from the pipe k is let up into the tun through the slightly-opened valve l and perforated pipe g, as above described, and quickly lowers the temperature of the wort to the point desired, the temperature being indicated by the thermometer j. As in the operation of boiling down, the wort loses its dissolved air necessary to the most vigorous action of the proper yeast fermentation. This process not only cools, but, as before stated, properly aerates, the liquor with-

out introducing ferments that would spoil it. Besides the usual methods of cooling hot wort, it is exposed to all the contaminating influence of ordinary unpurified air. Besides sustaining the proper yeast ferment, the aeration of the beer with purified or sterilized air kills that most dangerous and troublesome of all sickness in beer and ale known as the "butyric," as I have learned by many experiments. After the tun has been filled with hot wort the valve u of the funnel i is closed and the funnel filled with boiling-hot water; but after the wort is cooled sufficiently to admit of the yeast being added the valve u is opened and the water that was standing in the funnel allowed to run into the tun, and then the liquid yeast, as pure as may be obtained, is run into the cooled wort through the same funnel. The yeast can now be stirred or mixed up with the wort by injecting a little more air into the bottom of the tun. Air and gas passing from the tun escape by means of the branch or U-shaped pipe l' into the pipe M. The pump may be worked at a pressure of from one hundred and twenty to one hundred and seventy pounds, (more or less,) which will raise the temperature of the air thus being compressed to 400° Fahrenheit and upward.

When I speak of an "air-pump," I mean to include a pump that may be used for forcing either air or gas, or both, into the tuns.

I am aware that it has been proposed to filter the air introduced into the fermenting-vats; that it has also been proposed to "calcine" the air on its way to the wort by means of a flame playing upon a copper tube through which the air passes, and, finally, that it has been proposed to lead purified air which has been cooled to about 5° centigrade and is under feeble pressure into the fermenting-tanks, but without sterilization. The first of these propositions contemplates nothing more than is secured by the use of my filter A—to wit, the removal of dust and like impurities. The second contemplates merely the heating of the air by a flame and without retaining it in a vessel sufficiently long to secure the perfect sterilization, which is so essential to the successful carrying out of my process. While the third plan proposed contemplates only a feeble pressure, which cannot effect a heating to the air and thereby cause its sterilization.

Among the advantages claimed for my process is that it is carried out by a simple and compact apparatus by means of which new hot wort may be cooled in the tuns where it is to be fermented, and this, too, without exposure to common unpurified air, whereas by the usual methods of cooling hot wort it is aerated, it is true; but the aeration is slow and in open vats and the apparatus costly and cumbersome.

Another advantage resides in the fact that the cooling is done in such a way as to effect the best possible result with the least expense.

of power both in cooling new hot wort and in cooling fermenting wort. Furthermore, by surrounding the compressed-air filter and compressed-air reservoir with a thick non-conductor of heat and filling the compressed-air filter with non-combustible filtering material I am enabled to heat the air sufficiently to purify or sterilize it by the same apparatus and machinery used to refrigerate and aerate the wort or beer, and this, too, in a single continuous operation. While, therefore, I am aware that the filtering and heating of the air to be injected and the use of feebly-compressed air have before been proposed, I am not aware that any or all of these ideas have been practically carried out or applied, nor that the air has been filtered under compression, nor that the air has been brought to such a high temperature by compression and retained long enough in this condition to effect its sterilization.

Having thus described my invention, what I claim is—

1. The improvement in the process of manufacturing beer, &c., which consists in raising the temperature of a body of air by highly compressing it and confining it in this condition until the sterilization shall have been effected and then cooling the air and injecting

it into the wort, substantially as and for the purposes described.

2. In combination with a tun or vat, a compressed-air receiver D, an air-filter C, containing an incombustible filtering material, a pump B, connected with the filter, a non-conducting jacket surrounding the filter and receiver, and pipes connecting the receiver with the vats and with the filter.

3. In combination with the tuns or vats G, a pump or compressor B, an air-filter C, a receiver D for the compressed air, a coil or manifold E, a water-supply f, and a pipe k, leading from the coil to the vats, all substantially as shown.

4. In combination with an air pump or compressor B, an air-filter A, applied to the supply-pipe thereof, an air-filter C, applied to the discharge-pipe of the pump, a compressed-air receiver D, a cooling coil or manifold connected with the receiver, the tuns or vats, and suitable connecting-pipes.

In witness whereof I hereunto set my hand in the presence of two witnesses.

CHARLES F. LAWTON.
